UNITED STATES PATENT OFFICE

ROSS R. WEST, OF SAN MATEO, CALIFORNIA

VAULT VENTILATOR

Application filed January 4, 1930. Serial No. 418,548.

My invention relates to bank vaults and more particularly to an improved type of ventilating device such as is shown and described in my prior Patent No. 1,786,277 dated Dec. 23, 1930, entitled "Vault ventilators".

Bank vaults, as at present constructed, must comply with certain rigid specifications which will render the vault substantially immune from successful attack by drills or metal cutting torches. It is also important that the vault be fireproof and, as a result, such a vault will be practically air-tight when closed.

15 In order to make a vault of this type perfectly safe for the attendants and other employees to enter without fear of being suffocated, should they be accidentally or deliberately locked in the vault, it is necessary to 20 provide means of ventilation so that fresh air can be delivered to the interior of the vault, should such a need arise.

In providing such ventilation, however, it is essential that the means adopted will not 25 defeat the prime requisite of the vault, namely, security to its contents. It is therefore a consideration of my invention to provide a ventilating means which will permit the proper amount of ventilation and at the 30 same time be of such a nature as not to weaken the vault.

In most of the disclosures of the prior art, the ventilators provided afforded ventilation for the vaults by the natural circulation of 35 air through openings in the wall. Under ordinary circumstances this means of ventilation is sufficient, but under extreme conditions, such as are encountered in large vaults, I find that it is desirable to provide means for 40 producing a forced circulation of fresh air into and out of the vault, as disclosed in my above prior application. My present invention embodies many of the desirable characteristics of my previous application. This 45 prior ventilator, however, while very successful, is, owing to its structure, too expensive for some particular installations where a less expensive ventilator is desired. It is therefore a further object of my invention to 50 provide a means whereby the vault can be

efficiently ventilated by a forced circulation of air, which means is simple and economical to produce and can be operated from within the vault and which will not render the vault susceptible to successful attack.

55 Other features and advantages will appear as the description, taken in connection with the accompanying drawings, proceeds. In these drawings, I have shown by way of illustration a preferred embodiment of my invention, wherein—

Fig. 1 is a vertical sectional view of a vault wall showing my invention applied thereto and in its open position,

Fig. 2 is a view similar to Fig. 1, showing my device in its closed position,

Fig. 3 is an end elevation of my improved ventilator showing it in the position illustrated in Fig. 1,

Fig. 4 is a sectional view taken along line IV—IV of Fig. 1, and

Fig. 5 is a sectional view taken along line V—V of Fig. 1.

In the drawing, wherein like numerals refer to like parts throughout the several figures, 10 designates a member adapted to be embedded in a vault wall 11. The member 10 is illustrated in the drawings as being cylindrical in shape. It will be understood, however, that this member 10 may be of any desired configuration, the only limitation being that its inner opening will need be cylindrical. Mounted upon the outer end of the member 10 and secured thereto as by welding, there is shown an end closure member 12 and at the inner end of the member 10 there is shown a removably mounted end closure 13. These end closures 12 and 13 have passages therethrough which, when the parts are assembled, will remain in alignment.

90 Arranged within the member 10 and between the end members 12 and 13, I provide a plurality of alternately arranged rotatable and stationary discs 14 and 15, respectively. These discs may be of any desired thickness and any suitable number may be provided, the preferred arrangement being one wherein the alternate discs may be rotated in unison. These alternately arranged discs may be of any suitable material. In the preferred em- 100

bodiment of my invention, I contemplate providing discs of different characteristics, as for instance, alternate discs of copper and steel, the steel being resistant to drills and the copper resistant to torch attacks. It is conceivable also that discs of concrete or other suitable material might be used. The discs 14 and 15 are each provided with diametrically disposed openings which will coincide with the openings in the end members 12 and 13 when the rotatable elements 14 are rotated into a predetermined position and the stationary discs 15 are so disposed within the member 10 that their openings will always remain in alignment with the aforesaid openings in the end members 12 and 13. Extending through the inner end member 13 and the several discs 14 and 15, there is provided a central shaft 16. This shaft 16 is squared throughout the major portion of its length and at this portion engages squared openings in the center of the rotatable discs 14. At the point where the shaft 16 passes through the stationary disc 15, it will be understood that a circular opening is provided so that the squared shaft may rotate freely therein without disturbing their stationary condition. A suitable handle or crank 17 is provided on the inner end of the shaft 16 so that the shaft may be rotated through an angle of 90° to bring the openings in the respective discs 14 and 15 into and out of alignment with each other to either open the vault for ventilation or close it against attack.

Projecting into the upper opening, designated by the numeral 18, of the inner end member 13, there is shown the discharge outlet of a suitable electric fan or blower 19 which is so arranged that it will force air out through the upper openings through the bank vault ventilator and, by reason of a reduced pressure within the vault, cause fresh air to be drawn through the lower opening, designated by the numeral 20, into the vault. Mounted upon the blower 19, I provide a suitable switch 21 which, when operated, will serve to control the operation of the blower 19. This switch may be independently operable by the attendant after the ventilator has been moved to its open position, or it may be interlocked with the lever 17, as described and claimed in my prior application, so that the motor will be alternately started and stopped as the vault ventilator is respectively opened and closed.

In order to maintain the rotors normally out of registry with the ventilating openings in the stationary members 15 a latch member 22, of suitable construction, is employed which is adapted to be readily operated from a point adjacent to the handle 17 and at the same time appropriately engaging the outer rotor member 14, all as shown in Fig. 2. Mounted upon the end member 13 is a suitable safety or alarm switch 23. This alarm

23 is provided with a normally open circuit which is controlled by a plunger 24 extending down through the projecting end of the member 10 and against one of the rotatable discs 14. The adjacent disc 14 is also provided with a recessed portion 25 which will cooperate with the plunger 24 and permit it to move inwardly and close the alarm 23 when the ventilator is moved into its ventilating position, as shown. This alarm, it will be understood, will be also rendered operative should the end plate be removed for any reason whatsoever.

At the outer end of the member 10 it will be noted that the end closure member 12 is so designed that it forms an outwardly projecting flange which will effectively render any inward displacement of the body member 10 within the vault wall 11 impossible. It will also be noted that there is associated with the top and bottom openings 26 and 27, respectively, suitable tubular extensions 28 and 29 which cooperate with a suitable escutcheon plate 30 to form a finish on the exterior surface of the vault wall. In order that there be no direct draft created externally of the wall as a result of the blower 19, I also provide a louvre 31, adjacent the outer end of the tubular member 28, which serves to direct the circulating air upwardly against the ceiling. The tubular member 29, on the other hand, is left completely free of any louvre or other member so that in an emergency an operator within the vault may have a clear line of vision through the opening in the ventilator, should he for any reason want to observe conditions externally of the vault. The end member 12 is also shown as provided with a recess 32 into which the extreme end of the shaft 16 may be journaled.

In addition to the above specifically referred to features, it will be understood that my improved ventilator is provided with other safeguards and alarms such as are usually provided with devices of this character, and that I may also provide in conjunction with the rotating and stationary discs 14 and 15, various types of packings for the purpose of rendering the ventilator proof against the introduction of gases and/or liquids into the device with a view to destroying the same by an explosion.

In Fig. 3 of the drawing I have shown the lever or crank 17 thrown into the horizontally extending position, which is the position which it will assume when the vault ventilator is open, as illustrated in Fig. 1. This view also shows the manner of mounting the fan or blower 19 entirely upon the end closure member 13 and free of any connections whatsoever with the vault wall.

The sections shown in Figs. 4 and 5 clearly illustrate the manner of fixing the rotatable discs 14 upon the shaft 16 and the

stationary discs 15 within the member 10, the members 14 being fixed upon the shaft 16 by reason of the squared cross section, as illustrated in Fig. 4, and the stationary members being secured fixedly within the member 10 by reason of projections 33 formed upon the members 15 and which project into suitable keyways 34 in the member 10.

While I have, for the sake of clearness and in order to disclose my invention so that the same can be readily understood, described and illustrated specific devices and arrangements, I desire to have it understood that this invention is not limited to the specific means disclosed but may be embodied in other ways that will suggest themselves, in view of this broad disclosure, to persons skilled in the art. It is believed that this invention is broadly new and it is desired to claim it as such so that all such changes as come within the scope of the appended claims are to be considered as part of this invention.

Having thus described my invention, what I claim and desire to secure by Letters Patent is—

1. The combination with a vault wall, of a member embedded in and extending through said wall, a plurality of alternately arranged stationary and rotatable discs disposed within said member and filling the space between its ends each having an opening therethrough, and means for rotating said rotatable discs to bring their openings into or out of alignment with the openings in said stationary discs to provide or to prevent ventilating passages into the vault.

2. The combination with a vault wall, of a member embedded in and extending through said wall, end pieces secured at the ends of said member having aligned openings, a plurality of alternately arranged stationary and rotatable discs disposed within said member between said end pieces having co-operating openings therethrough, and means for rotating said rotatable discs to bring their openings into or out of alignment with the openings in said stationary discs to provide or to prevent a ventilating passageway into the vault.

3. In a vault ventilator, the combination of a member embedded in and extending through the wall of the vault, a plurality of alternately arranged stationary and rotatable discs disposed axially in alignment within said member and in contact with each other and having openings adapted to register, and means for rotating said rotatable discs to bring the openings therein into or out of register with the openings of said stationary discs to provide or to prevent a ventilating passageway therethrough.

4. In a vault ventilator, the combination of a sleeve embedded in and extending through the wall of the vault, a plurality of

alternately arranged stationary and rotatable discs disposed axially in alignment within said sleeve and having openings adapted to register, means for rotating said rotatable discs to bring the openings therein into or out of register with the openings of said stationary discs to provide or to prevent a ventilating passageway therethrough when in their assembled position within said sleeve, and means upon the inner end of said sleeve adapted to retain said discs within said sleeve and permit their removal and assembly from within the vault only.

5. The combination with a vault wall, of a plurality of alternately arranged stationary and rotatable discs within said wall, said discs each having corresponding openings therethrough, and means for rotating said rotatable discs to bring their openings into or out of alignment with the openings in said stationary discs, said discs being closely adjacent each other, whereby when the openings of the rotatable discs are out of alignment with the openings of the stationary discs, said discs present a substantially solid mass.

6. The combination with a vault wall, of a sleeve embedded in and extending through said wall, a plurality of alternately arranged stationary and rotatable discs within said sleeve, said discs each having corresponding openings therethrough, and means for rotating said rotatable discs to bring their openings into or out of alignment with the openings in said stationary discs, said discs being closely adjacent each other, whereby when the openings of the rotatable discs are out of alignment with the openings of the stationary discs, said discs and sleeve present a substantially solid mass, adjacent discs having different burglar-proof characteristics.
